UNITED STATES PATENT OFFICE.

WILLIAM C. WEAVER, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,353,872.

Specification of Letters Patent. Patented Sept. 28, 1920.

Application filed March 25, 1918, Serial No. 224,516. Renewed March 5, 1920. Serial No. 363,592.

To all whom it may concern:

Be it known that I, WILLIAM C. WEAVER, a citizen of the United States, residing at East Orange, in the county of Essex, State of New Jersey, have invented certain new and useful Improvements in Telephone-Exchange Systems, of which the following is a full, clear, concise, and exact description.

This invention relates to telephone exchange systems and more particularly to such systems in which operator-controlled connecting circuits are employed.

In systems of this character it is frequently desirable to supplement the ordinary visual disconnection signal produced by a change in the condition of the signaling device upon the restoration of the receiver to the switchhook at one of the subscribers' stations interconnected for conversational purposes, by an effective auxiliary signal, preferably audible, which will invariably attract the attention of the operator. A peremptory signal of this nature tends to improve the service by promoting prompt disconnection of the connecting circuit upon the completion of the conversation thereover and thereby reducing the number of subscribers' lines and connecting circuits which are ineffectively associated. Such a signal also serves to notify the operator readily that a recall is being initiated by one of the connected stations and enables the supervisor to more closely observe the service being rendered.

In accordance with a feature of this invention either or both supervisory relays of a connecting circuit are provided with means operable during each operation and each release of the associated relay to provide a momentary signal, which preferably may be audible in addition to the usual permanent change in the condition of the visual signaling device.

It is thought that the invention will be clearly understood from the following specification and the annexed drawing, Figure 1 of which diagrammatically illustrates one embodiment of the invention; while Fig. 2 illustrates a modified form thereof.

In Fig. 1 of the drawing a cord or connecting circuit C, which may be of any

usual type, and of which only sufficient is shown to properly illustrate the invention, is provided at a central station for joining the subscribers' stations A and B for conversational purposes. The supervisory relays 1 and 2 are each provided with contacts of the make-before-break type which, either upon the release, or upon the operation of the relay, cause an impulse of current to flow through an auxiliary relay 3, which relay may preferably be common to several cord circuits, thereby causing a momentary operation of a suitable audible signaling device 4 to supplement the usual accompanying change in condition of the associated supervisory signaling lamp. The relay 3 may be shunted by condenser 20 for the well-known purpose of aiding in the quick response of the relay.

Fig. 2 illustrates a slightly modified form of connecting circuit which may be used instead of the connecting circuit C shown in Fig. 1. Such portions of this circuit as are identical with the circuit of Fig. 1 have been omitted. In the modified system shown in Fig. 2, the usual supervisory relays 1 and 2 are equipped with the ordinary contacts and battery is supplied to such contacts through the windings of a differential relay 21 which is provided with make-before-break contacts for controlling the operation of the auxiliary relay 3.

It is thought that the invention may be more fully comprehended from the following description of the operation of the system shown on the drawings.

Referring to Fig. 1, assume that station A initiates a call, thereby causing the lighting of lamp 5 in the usual manner by the operation of the line relay 6. The operator answers the call by inserting plug 7 of connecting circuit C into jack 8, thereby operating the cutoff relay 9 over a circuit from battery through lamp 10, resistance 11, sleeve contacts of plug 7 and jack 8 and winding of relay 9 to ground, and consequently releasing the line relay 6 and extinguishing the line lamp 5 in the usual manner. Relay 1 also operates in the ordinary manner over a circuit established from battery through a winding of repeating coil 13, winding of relay 1, ring contacts of the

plug 7 and jack 8 through the switchhook contacts at station A, tip contacts of jack 8 and plug 7, and a second winding of repeating coil 13 to ground. The operation of relay 1 shunts the lamp 10 by the resistance 12, and thereby extinguishes the lamp in the usual manner. During the operation of relay 1 the left-hand alternate contact is closed before the normal contact is opened and a temporary circuit is therefore established from battery through left-hand alternate and normal contacts of relay 1 and winding of relay 3 to ground. Relay 3 thereupon completes a circuit, for a corresponding period, from battery through the audible signal device 4 and contact of relay 3 to ground, thereby producing an audible signal. When relay 1 is completely operated and its normal contact is opened, relay 3 releases and causes the cessation of the audible signal by opening the circuit of the device 4.

Upon ascertaining that a connection is desired with station B, the operator inserts plug 14 into jack 15, thereby operating cutoff relay 16 and lighting supervisory lamp 17 in the ordinary manner over a circuit extending from battery through lamp 17, resistance 18, sleeve contacts of plug 14 and jack 15 and winding of relay 16 to ground. The operator signals the subscriber at station B in any suitable manner, and upon the removal of the receiver from the switchhook at station B in answering the call a circuit is completed which causes the operation of relay 2 over a circuit established from battery through a winding of repeating coil 13, winding of relay 2, ring contacts of plug 14 and jack 15, switchhook contacts of station B, tip contacts of jack 15 and plug 14 and a second winding of repeating coil 13 to ground and the consequent operations in a manner similar to that described for relay 1.

Assuming that the conversation is completed and the receiver at station A is restored, relay 1 is thereupon released due to the opening of its circuit at station A, and by removing the shunt about the lamp 10 effects the lighting of this lamp in the ordinary manner. While releasing, however, relay 1 closes its normal contact prior to the opening of its left-hand alternate contact and completes a temporary circuit for relay 3, similar to the circuit previously described, to cause a momentary operation of the device 4 to produce a corresponding audible signal. When the receiver of station B is restored, relay 2 will be operated in a similar manner, causing the lighting of lamp 17 and a second momentary audible signal. All apparatus returns to normal upon the removal of both plugs of the connecting circuit from the jacks of the connecting lines.

In case station A desires to initiate a re-

call the movement of the switchhook at such station will in the usual manner alternately energize and deenergize relay 1 and thereby flash lamp 10. A momentary audible signal will be produced by the device 4 during each operation and each release of relay 1 and by means of these successive signals the desire for another connection may be readily recognized by the operator as well as by the supervisor. Station B may also notify the operator in the same manner when a recall is desired.

Referring to Fig. 2, assume that a call initiated by station A has been answered by the insertion of plug 7 of the modified connecting circuit C into the jack 8. The line lamp 5 is extinguished by the operation of the cutoff relay 9 and the supervisory relay 1 operates as described in connection with Fig. 1. Supervisory lamp 10 is shunted by a circuit proceeding from battery through the left-hand winding of relay 21, contact of relay 1, resistances 12 and 11, sleeve contacts of plug 7 and jack 8, and winding of cutoff relay 9 to ground. Relay 21 thereupon operates and since the left-hand alternate contact thereof closes before the normal contact opens, a temporary circuit is established from battery through the left-hand alternate and normal contacts of relay 21 and winding of relay 3 to ground. Relay 3 thereupon operates and completes a circuit for a corresponding period from battery through the signaling device 4, contact of relay 3 to ground, thereby producing an audible signal. When relay 21 is completely operated the normal contact thereof opens, releasing relay 3 and causing the cessation of the audible signal by interrupting the circuit through the signaling device 4.

Upon ascertaining that a connection is desired with station B, the operator inserts plug 14 of the modified connecting circuit into jack 15, operating cutoff relay 16, thus lighting supervisory lamp 17, and then signals station B, as described in connection with Fig. 1. The removal of the receiver from the switchhook at station B also causes the operation of relay 2 as in the former case. The supervisory lamp 17 is shunted by a circuit established from battery through the right-hand winding of relay 121, contact of relay 2, resistances 19 and 18, sleeve contacts of plug 14 and jack 15, and winding of cutoff relay 16 to ground. Relay 21 thereupon releases, due to the differential arrangement of the windings thereof and in releasing closes the normal contact before opening the left-hand alternate contact, thereby establishing a temporary circuit from battery through the left-hand alternate and normal contacts of relay 21 and the winding of relay 3 to ground. Relay 3 thereupon operates, closing a circuit for a corresponding period from battery

through signaling device 4, and contact of relay 3 to ground, thereby producing an audible signal such as was produced in connection with the operation of relay 21.

- 5 Upon the completion of the conversation, the restoration of the receiver to its switchhook at station A releases relay 1 and lights supervisory lamp 10 as described in connection with Fig. 1. Relay 21 operates due to 10 the continued flow of current through the right hand winding, thereby causing a similar momentary audible signal to be produced by the signaling device 4. Upon the subsequent restoration of the receiver at station B, relay 2 is released, lighting supervisory lamp 17 and, due to the interruption of the circuit through the right hand winding, relay 21 releases. Another similar audible signal is thereupon produced by the 15 signaling device 4. Upon the disconnection of both plugs the apparatus returns to normal.

It will also be evident that the movement of the switchhook at either station in connection with a recall will produce a series of 20 momentary audible signals similar to that produced in connection with the embodiment shown in Fig. 1.

While audible signals are produced upon 25 the answering of a call by the operator and upon the answer of the called station, the service is not adversely affected thereby, since they are merely incidental to operations involved in the establishing of the 30 connection.

Although the invention is shown and described as being associated with each supervisory relay, it may be desirable in some cases to furnish the additional signaling 35 device in connection with the answering end of the link circuit only, since recalls are usually originated by the calling party and the restoration of the receiver at such station may serve to cause the operation of the 40 disconnect signal.

What is claimed is:

1. In a telephone exchange system, a plurality of lines terminating at a central office, a link circuit thereat for interconnecting the 50 lines, a supervisory relay for the link circuit adapted to control a supervisory signaling device, an auxiliary relay, means controlled by the supervisory relay to send an impulse of current through the winding of the auxiliary relay upon each energization and each deenergization of the supervisory relay, and an auxiliary signaling device controlled by the auxiliary relay for producing an additional momentary signal for each signal produced by the supervisory signaling device.

2. In a telephone exchange system, a plurality of lines terminating at a central office, a link circuit thereat for interconnecting the lines, a supervisory relay for the link circuit

adapted to control a visual supervisory signaling device, an auxiliary relay operable during each operating and each releasing period of the supervisory relay, and an auxiliary signaling device controlled by the auxiliary relay to produce a momentary audible 65 70 signal for each operation of the auxiliary relay.

3. In a telephone exchange system, a plurality of lines terminating at a central office, a link circuit thereat for interconnecting the 75 lines, a supervisory relay for controlling the supervisory signaling device, an auxiliary relay, a temporary operating circuit for the auxiliary relay closed through contacts of the supervisory relay during each operating 80 and each releasing period thereof, and an auxiliary signaling device adapted to produce a momentary signal upon each operation of the auxiliary relay.

4. In a telephone exchange system, a plurality of lines terminating at a central office, a link circuit thereat for interconnecting the lines, a supervisory relay for each end of the link circuit adapted to control a supervisory signaling device, an auxiliary relay, 90 means controlled by either supervisory relay to send an impulse of current through the winding of the auxiliary relay upon each energization and each deenergization of either supervisory relay, and an auxiliary 95 signaling device controlled by the auxiliary relay.

5. In a telephone exchange system, a plurality of lines terminating at a central office, a link circuit thereat for interconnecting the 100 lines, a supervisory relay for each end of the link circuit for controlling the condition of an associated supervisory signaling device, an auxiliary relay, a temporary operating circuit for the auxiliary relay closed through contacts of each supervisory relay during each operating and each releasing period thereof, and an auxiliary signaling device controlled by the auxiliary relay to produce 105 signals similar in character upon each 110 change in condition of either supervisory signaling device.

6. In a telephone exchange system, a plurality of lines terminating at a central office, a link circuit thereat for interconnecting the lines, a supervisory relay for the link circuit for controlling a supervisory signaling device, an auxiliary relay, a passing contact for the supervisory relay adapted to send an impulse of current through the winding of the auxiliary relay upon each energization and each deenergization of the supervisory relay, and an auxiliary signaling device controlled by the auxiliary relay.

In witness whereof, I hereunto subscribe 125 my name this 19th day of March, A. D. 1918.

WILLIAM C. WEAVER.
